UNITED STATES PATENT OFFICE.

WILLIAM I. RAVERT, OF HAZLETON, PENNSYLVANIA, ASSIGNOR TO A. W. DRAKE MANUFACTURING CO., OF HAZLETON, PENNSYLVANIA, A CORPORATION OF PENNSYLVANIA.

MINIATURE FENCE.

1,426,215.

Specification of Letters Patent. Patented Aug. 15, 1922.

Application filed June 8, 1921. Serial No. 476,028.

To all whom it may concern:

Be it known that I, WILLIAM I. RAVERT, a citizen of the United States, residing at Hazleton, in the county of Luzerne and State 5 of Pennsylvania, have invented new and useful Improvements in Miniature Fences, of which the following is a specification.

This invention relates to fences and particularly to miniature fences and gates for 10 ornamental purposes for use in connection with Christmas trees, etc.

The object is to provide a fence of this character composed of sections or panels of various predetermined lengths readily attachable to or detachable from supporting posts, and of such simple construction as to be readily manufactured in large quantities and sold at a low cost, the said attaching means permitting of the sections being 15 placed and supported in any desired angular relation to the adjacent panels or sections so as to form an enclosure of any desired shape.

Another object is to provide a sectional fence of this class which permits of the introduction of single or double gates at any desired point where the supporting posts occur, said gates being capable of swinging in either direction and of being supported in 20 any open position, the said panels or sections, gates and supporting posts being easily and quickly knocked down and packed in a box for shipment or storage.

A further object is to provide a fence in 25 which the sections may not accidentally pull apart or become detached from the post, the latter serving at all times to maintain the fence in upstanding position, whether the same are secured to the floor or other support or not.

A full and complete understanding of the invention may be obtained from a consideration of the following detailed description, taken in connection with the accompanying 30 drawings forming a part of this specification, it being understood that while the drawings show a practical form of the invention, the latter is not confined to strict conformity therewith, but may be changed or modified so long as such changes or modifications mark no material departure from the salient features of the invention, as specifically pointed out in the appended claims.

In the drawings, in which similar refer-

ence characters designate corresponding parts throughout the several figures:

Figure 1 is a plan view of the improved miniature fence, having a single gate included therewith and shown defining a rectangular area.

Figure 2 is a detail plan view of two of the single gates arranged in a pair to form a double gate.

Figure 3 is an elevation, on an enlarged scale of one of the long panels.

Figure 4 is a similar view of a single gate and its manner of mounting.

Figure 5 is a horizontal section through one of the posts.

In the manufacture of the article as herein designed, the object has been to reduce to a minimum the number of parts necessary to form a self-sustaining fence capable of assuming the various shapes that may be desired, and to provide a fence that may be readily added to, to lengthen the same by merely attaching additional panels or sections, and to reduce to a minimum special parts requiring the use of special machinery or dies, etc. to form the same, such as castings or stampings, so that the said panels may be produced at the lowest possible cost.

The fence, therefore, comprises suitable long and short sections, posts for the connection of the same thereto, and gates which may be hung singly or in pairs upon any one of the said posts, the whole being adapted to enclose any size area and in any desired contour.

As illustrated in the drawing the fence comprises a series of long panels or sections A to be used for connection to supporting posts B for encircling or enclosing a field or area of any desired shape, and a plurality of shorter panels or sections C which, while 95 they may be fewer in number than the long sections, are found advantageous for use in properly connecting up, where gates D are interposed in the fence line.

Each of the parts enumerated are self-contained, there being no small parts such as fastening means to be used in the attachment of the panels or the gates to the posts, and which might easily become lost or deranged in the operation of connecting the 100 several parts together.

The panels or sections A and C each comprise upper and lower horizontally disposed,

longitudinal bars 1 and 2, preferably formed of a small round rod of some strong wood rigidly secured together in their proper spaced relation by vertically disposed 5 pickets or palings 3, preferably formed of lengths of wire reed or the like bent into a semi-circle at their central portions, as at 4, to form the rounded top of the paling, and to provide a pair of the palings 3, 10 spaced apart and integrally joined together, the terminals passing through suitable apertures in the bars 1 and 2 and frictionally engaging the same to maintain the said bars in proper spaced relation. The semi-circular tops of the palings overlap each other, as clearly shown in Figure 3 of the drawing, in such manner as to preferably provide equally spaced palings the arms of one member comprising every fourth vertical paling, though any other desired spacing may 15 be adopted. This construction of the sections is not essential as any other design will serve the purpose equally as well.

The ends of the bars 1 and 2 extend somewhat beyond the last vertical arm of each outermost paling, and in each of these ends a suitable bore is provided extending inwardly to within a short distance of the adjacent paling. Into these bores are adapted 30 to be driven the terminals 5 of a stiff wire hinge member comprising upper eyes 6 and lower eyes 7 where connected to the terminals 5, and a connecting vertical portion 8 composed of the intermediate portion of 35 the wire forming the hinge member, the said connecting portion being vertically disposed and lying in substantial alinement with the ends of the bars 1 and 2 and substantially forming a continuation of the 40 series of palings.

The eyes 6 and 7 are horizontally disposed and extend in a line with the longitudinal center line of the bars 1 and 2, and one of the hinge members of each of the panels 45 or sections A and C, is provided with a depending foot 9, formed by extending the connecting member 8 thereof downwardly somewhat below the lower ends of the palings 3 where projecting below the lower bar 50 2, and then returning the wire upon itself to connect to the lower eye 7, as clearly shown in Figure 3 of the drawing.

The posts B are formed of suitable wood, turned to a diameter to freely enter the eyes 55 6 and 7 of the panels A and B, and they have their upper ends suitably formed into ornamental knobs or other shapes, while their lower ends are attached, as by screws 10, to metal discs 11 having their margins 60 turned downwardly to form peripheral flanges 12 adapted to rest upon the floor or other support, and to provide space for the head of the screw 10 and also to avoid any wobbling or rocking of the base member 65 11 together with its attached post B.

The base member or disc 11 is also provided with an aperture 13 of sufficient diameter to pass over the head of a fastening screw 14 adapted to hold the base to the floor or support, and said aperture is provided with 70 an extension adapted to receive the shank of said screw when the base is rotated as will be readily understood.

The gates D are provided with upper and lower, horizontally disposed, longitudinal bars 1^a and 2^a, joined together by vertical end posts 15, and the said bars 1^a and 2^a are connected by palings 3^a formed similarly to the aforesaid palings 3. One of the vertical posts is provided with a hinge member 75 formed similarly to the first described hinge members and provided with the depending foot 9.

In assembling the fence it has been found advantageous to lay the members flat upon 85 a table, floor or other support, a pair of sections or panels, say two of the long ones A being arranged adjacent to each other with the eyes 6 and 7 of that hinge member having the foot 9 located beneath the eyes of 90 the adjacent hinge member, when the post is introduced through the several alined eyes. By associating the desired number of panels together in this manner, with the bases 11 of all the posts arranged alike and 95 adjacent to the lower ends of the palings, and the short sections C interposed where necessary to adapt the fence for the use of the gate or gates D, the connected members may then be righted or set up vertically and the 100 last connection made, when the finished fence will remain in position, after which the screws 14 may be applied where the fence is to remain permanently, or they may be dispensed with if desired, as the structure is self-sustaining.

When properly set up, with the eyes having the feet 9 beneath the adjacent eyes of the next panel, the bars 1 and 2 are all arranged substantially on a level and supported by the several feet 9 resting upon the bases 11 and, as shown in Fig. 4, the eyes of the gate D will support the footless end of the adjacent panel at proper elevation and allow the gate to turn about the hinge 115 post B to assume any open position in either direction.

When a single gate D is used, the same is applied to the post B to which the hinge element of the adjacent panel C without the foot 9 is also attached. The eyes 6 and 7 of said panel are then placed between the eyes of said gate hinge, the latter eyes being spaced slightly farther apart to permit of such arrangement. The gate foot 9 of these 120 supports the adjacent end of the panel in elevated position but the gate is free to be rotated.

It will be readily seen that with the other gate post sufficiently removed from the first 130

named post, a second gate D, identical in construction to the first gate, may be applied, in which event the eyes of the second gate are each arranged above the eyes 6 5 and 7 of the adjacent panel C which in this case are provided with the foot 9 bearing on the base 11 and not only supporting the panel but also the second gate in elevated position.

10 From the foregoing it will be seen that an extremely simple, light, strong and durable fence structure has been provided, which is admirably adapted for use in connection with Christmas trees or in like use, being 15 easily set up or assembled to assume any desired shape, either with or without partition fences, and that the same may be readily knocked down and stored away for future use, or for shipment, and that the same may 20 be cheaply manufactured and sold at a low cost in sets of any desired numbers and combinations.

What is claimed is:—

1. A toy fence, comprising separate posts, 25 each having extended bases, and separate panels, connecting rings located on each end of a panel, the connecting rings of the adjacent ends of the panels adapted to be slipped on a post in superposed relation, and a foot 30 on one end of each panel adapted to rest on the base of said post and support the panels in swinging relation spaced above the horizontal plane of the post base.

2. A toy fence comprising separate posts, 35 each having extended bases, and separate panels, and means for connecting the posts to the panels, said means comprising spaced eyes and a vertical portion joining the eyes, said means being secured to the panel with

the eyes adapted to encircle the post, and a 40 foot provided on the connecting means and resting upon the post base for supporting the adjacent panels connected to said posts above the horizontal plane of the post bases.

3. A toy fence comprising separate posts 45 and separate panels, the panels being formed of longitudinal bars with wire palings and means for connecting the posts and panels consisting of a wire member formed of a single piece with upper and lower spaced 50 eyes and a connecting substantially vertical portion, the ends of the wire forming said member being secured in the ends of the bars of the panels so that the eyes are in horizontal alinement with said bars and the connecting portion is spaced from the palings 55 of the panel and adapted to function as a paling.

4. A toy fence comprising separate posts each having extended bases and separate 60 panels, the panels being formed of longitudinal bars with palings, and means for connecting the posts and panels consisting of a wire member formed of a single piece with upper and lower spaced eyes and a 65 connecting substantially vertical portion, the ends of the wire forming said member being secured in the ends of the bars of the panels so that the eyes are in horizontal alinement with said bars and the connecting portion is 70 spaced from the wire palings of the panel and adapted to function as a paling, and a foot provided on the bottom of said member to ride upon the post bases.

In testimony, that I claim the foregoing 75 as my own, I have hereto affixed my signature.

WILLIAM I. RAVERT.
